ROASTING DEVICE

Joseph Arthur Dumas, Brooklyn, N. Y., assignor
of one-half to Romaine B. Stoker, Mount Ver-
non, N. Y.

Application August 5, 1939, Serial No. 288,544

5 Claims. (Cl. 219—19)

This invention relates to a machine for roasting frankfurters and the like and has for an object to provide a roaster in which the frankfurters or the like are automatically turned for the even application of heat on all sides thereof.

Another object is to provide a device of the above type having means for quickly bringing certain of the heating rolls up to the desired temperature.

Another object is to provide a rotatable heating roll having novel and improved details of construction.

Another object is to provide a simple and efficient mechanism for making electrical connections to the rotating rolls.

Another object is to provide a simple, dependable, efficient and commercially practical device of the type above indicated.

Various other objects and advantages will be apparent as the nature of the invention is more fully disclosed.

The novel features which are believed to be characteristic of this invention are more fully pointed out in the claims appended hereto. The invention itself may, however, be better understood by referring to the following description, taken in connection with the accompanying drawings, in which a specific embodiment thereof has been set forth for purposes of illustration.

In the drawings:

Fig. 1 is a top plan view of a roasting device embodying the present invention, with parts broken away to show the details of construction.

Fig. 2 is a vertical longitudinal section taken on the line 2—2 of Fig. 1.

Figs. 3, 4 and 5 are vertical transverse sections taken on the lines 3—3, 4—4 and 5—5 respectively of Fig. 1.

Fig. 6 is a broken section through a heating roll showing the construction thereof, and

Fig. 7 is a schematic wiring diagram showing the connections of the various rolls.

Referring to the embodiment of the invention illustrated in the drawings, the roasting device is shown in Fig. 1 as comprising a rectangular frame 10 having a pair of transverse partitions 11 and 12 in which a plurality of heating rolls 14 are journaled. The rolls 14, as shown more in detail in Fig. 6, each comprise a metal tube 15 having an inner liner 16 of refractory material such as porcelain or the like. A heating coil 17 is disposed within the liner 16. Each end of the liner 16 is closed by a disc 18 of insulating material which is held in place by a hub 19 having an annular flange 20 which is secured within

the tube 15. The hubs 19 comprise the bearing surface for the roll and are suitably journaled in the partitions 11 and 12. A contact bolt 21 extends through an insulating bushing 22 within the hub 19. The end of the heating coil 17 is electrically connected to the head 23 of said bolt. The bolt is held in position by nuts 24 and is provided with a tip 25 which forms a contact point for making outside contact to the heating coil 17. One of the hubs 19 carries a worm wheel 10 26 by which the roll 14 is driven, as will be described.

The tips 25 of the bolts 21 engage contact plungers 30 which are slidably mounted in walls 31 and are spring pressed inwardly by spring contact members 32. The contact members 32 are mounted on the walls 31 and provide means for making contact to an external circuit.

The worm wheels 26 are all driven by a worm shaft 35 which is mounted on suitable brackets 20 36 secured to the frame 10 in any convenient manner and is driven by a worm gear 37 carried by a shaft 38. The shaft 38 is driven through a suitable reduction gear driven by means of an electric motor 40 which is mounted within the frame 10 in a compartment formed between the wall 31 and the end of said frame. The motor may be provided with a fan 41 to circulate cooling air therefrom. The ends of the motor compartment may be provided with ventilating apertures 30 42 to permit the proper circulation of air over the motor.

The electrical connections are shown in detail in Fig. 7. A connection is made from one of a pair of mains 45 to the contact strip 32 associated 33 with an end roll 14. The other contact strips are suitably interconnected as by leads 46 to 50 for connecting the various rolls in series. The connection is made from the final contact strip by a lead 51 to contact 52 of a double throw switch 53, 40 the blade of which is connected by a lead 54 to a switch 55 and thence by a lead 56 to the other side of the main 45. The second contact 57 of the double throw switch 53 is connected by a line 58 to the lead 48 interconnecting the two center 43 rolls. A connection is also made from the lead 47 through a push switch 59 and lead 60 to the return side of the main 45. The motor 40 is connected across the main 45 through a switch 61. Switches 53, 55 and 61 may be mounted on the frame 10 as shown in Fig. 1. The switch 59 is shown as mounted on the end of the frame 10 and provided with a plunger 62 which is adapted to be readily engaged and held in by the operator, for the purpose to be described. The compart-

ments between the ends of the frame 10 and the partitions 11 and 12 respectively, may be closed by hot plates 65 and 66. These plates may be of standard construction and may be provided with the usual heating elements which may be connected by means of a switch 67 across the main 45. In certain instances one of the plates such as the plate 66 may constitute a supporting tray only in which event the heating may be omitted therefrom.

In the operation of this device the current supply to the rolls 14 is controlled by the switch 55 which is normally closed when the device is operating. The switch 61 serves to close the circuit to the motor 40 as to cause the rolls to be driven thereby at a comparatively slow speed. In normal operation the rolls are series connected through the contact 52 of the switch 53 so that they are all maintained at proper roasting temperature. The frankfurters or the like are placed between the various rolls and are slowly turned as the rolls are rotated so that they are evenly roasted on all sides.

In certain instances it may be desired to bring certain of the rolls to a higher temperature. For this purpose the switch 53 is operated to make contact with the contact 57 thereof, thereby connecting the three top rolls, as viewed in Fig. 7, in series across the main 45. This of course causes increased current to flow through these rolls. At the same time the remaining three rolls are entirely disconnected. After the first three rolls have been brought to the desired high temperature the switch 53 may be again actuated to connect all of the rolls in series. The lower rolls, as seen in Fig. 7, will then operate at a temperature lower than the upper rolls and may be used for keeping the frankfurters warm after they have been roasted on the hotter rolls. It is to be understood, of course, that this sequence of operations is illustrative only and that various combinations may be effected as desired.

The switch 62 serves to connect two rolls in series across the main 45. This is for the purpose of heating up two of the rolls rapidly, as for example, when the apparatus is started in operation in the morning. A considerable period of time might be required for heating all of the rolls to a roasting temperature. The switch 59 accordingly permits certain of the elements to be quickly brought to operating temperature and avoids necessity for waiting until the entire machine has been brought to temperature before beginning roasting operations.

The hot plates 65 and 66 may be used for toasting buns or the like to be used with the frankfurters or may be used for keeping the frankfurters warm after they have been roasted on the rolls 14.

It is to be noted that the individual rolls may be readily removed from the apparatus without disturbing the electrical connections and that an electrical contact is always maintained to the rotating rolls by means of the spring pressed contact members 30 and the rotating tips 35 of the contact bolts 21.

The driving mechanism may be modified in various ways. For example, the motor may be connected to drive a set of fiber discs or the like which may be mounted on the partition 12. Similar idler discs may be mounted on the partition

11 in a position such that the rolls 14 may merely rest upon the discs and be driven thereby. In that event, the electrical contact pins 30 may be mounted in the partitions 11 and 12 so that the rolls 14 may be lifted out of the machine for purposes of cleaning, repair or replacement without requiring adjustment or modification of the driving mechanism or of the electric connections.

While the device is intended primarily for the roasting of frankfurters or the like, it is to be understood that it may be used for other purposes. Furthermore the specific construction has been shown for purposes of illustration only and various changes and embodiments may be made therein as will be readily apparent to a person skilled in the art. Certain specific terms have been mentioned herein for convenience in referring to various details of the invention but the invention is only to be restricted in accordance with the following claims.

I claim:

1. A roasting device comprising a pair of parallel rolls spaced to receive and support an article to be roasted, means rotating said rolls in the same direction so as to turn said article during the roasting operation, and heating means for said rolls.

2. A roasting device comprising a pair of parallel rolls spaced to receive and support an article to be roasted, means rotating said rolls in the same direction so as to turn said article during the roasting operation, said rolls having electrical heating elements disposed therein and means supplying heating current thereto.

3. A roasting device comprising a pair of parallel rolls spaced to receive and support an article to be roasted, means rotating said rolls in the same direction so as to turn said article during the roasting operation, said rolls each having electrical heating elements disposed therein, contact means connected to said heating elements and located at the ends of said rolls and means making electrical contact with said contact means for supplying heating current to said heating elements.

4. A roasting device comprising a pair of parallel rolls spaced to receive and support an article to be roasted, means rotating said rolls in the same direction so as to turn said article during the roasting operation, electrical heating elements disposed within said rolls, axially disposed contact members carried by said rolls and connected to said heating elements and stationary contact means engaging said contact members for supplying heating current to said heating elements.

5. A roasting machine for frankfurters or the like comprising a plurality of parallel rolls spaced to receive and support said frankfurters therebetween, means driving all of said rolls in the same direction for causing said frankfurters to be continuously turned as they are roasted thereby, electrical heating elements disposed in each of said rolls, means normally connecting all of said elements in series, a supply line for supplying heating current thereto and switch means associated with said device for disconnecting certain of said rolls and connecting the remaining elements in series across said line for supplying increased heating current to said certain elements.

JOSEPH ARTHUR DUMAS.
